DESIGN FOR A SHOE

Julius A. Goldberg, Highland Park, Ill.

Application March 4, 1935, Serial No. 55,710

Term of patent 3½ years

To all whom it may concern:

Be it known that I, Julius A. Goldberg, a citizen of the United States, and a resident of Highland Park, in Lake County and State of Illinois, have invented a new, original, and ornamental Design for a Shoe, of which the following is a specification, reference being had to the accompanying drawing, forming part thereof.

In the drawing:

Figure 1 is a plan view of a shoe, embodying my new design.

Figure 2 is a side elevation of the shoe.

I claim:

The ornamental design for a shoe substantially as shown.

JULIUS A. GOLDBERG.
